CONTAINER

John M. Hothersall, Brooklyn, N. Y., assignor to
 American Can Company, New York, N. Y., a
 corporation of New Jersey

Application June 25, 1935, Serial No. 28,368

4 Claims. (Cl. 220—54)

The present invention relates to tearing strip key opening containers or cans and has particular reference to a tongue construction which reduces the container cost without detracting 5 from the full benefit of a key engaging tongue part for the removal of the tearing strip in the opening of the container.

An object of the invention is the provision of 10 a tearing strip container or can having a specially constructed tongue which is formed in the edge of the blank from which the body is made and which allows for manufacture of the container from a smaller body blank with the resulting saving in container cost.

15 A further object of the invention is the provision of a container or can of the character described having a tongue part formed adjacent one end of a tearing strip section which is outlined by score lines in the body wall, this tongue 20 being made effective for engagement with an opening key by bending from its initial position in the blank to extended position beyond the end of the tearing strip.

A still further object of the invention is the 25 provision of a tearing strip container or can formed with a side seam having a part of the seam edges interlocked in a lock seam and a part overlapped in a lapped seam the tongue extension of the tearing strip being formed by bending 30 an edge section of the blank which is adjacent to that which enters into the lap part of the side seam.

Numerous other objects and advantages of the 35 invention will be apparent as it is better understood from the following description, which, taken in connection with the accompanying drawing, discloses a preferred embodiment thereof.

Referring to the drawing:

Figure 1 is a perspective view, parts being 40 broken away disclosing a tearing strip container embodying the present invention;

Fig. 2 is a sectional fragmentary view on an enlarged scale taken just above the tearing strip tongue as viewed along the line 2—2 in Fig. 1;

45 Figs. 3, 4, and 5 are corner fragments of a body blank illustrating the position of the tongue section relative to the tearing strip in three different stages of its construction;

Fig. 6 is a sectional detail of the tongue construction in an intermediate stage as viewed substantially along the line 6—6 in Fig. 4; and

Fig. 7 is a similar view showing the formation of the tongue at the completion of the tongue bending operation, this view being a section 55 taken substantially along the line 7—7 in Fig. 5.

A popular type of tearing strip container or can is one having a tearing strip which encircles the can body with the key engaging tongue of the tearing strip an integral part of the body. This tongue extends beyond the edge of the can seam 5 and such a can requires a body blank long enough to include the tongue. A considerable waste of material results in blanking out this projecting tongue length and a great deal of the edge of the blank must be cut away and lost in order to 10 produce the projecting tongue.

The present invention effects a considerable saving in the material in the body blank by doing away with this loss or waste of the body blank edge. In the present invention the tongue 15 is embodied within the outlines of the blank instead of projecting beyond. The tongue is formed inside of one edge of the blank and is partially severed as it remains in position with its longitudinal extent adjacent the blank edge. In other 20 words it is at right angles to the tearing strip.

The tearing strip is preferably formed in the 25 body wall by score lines which extend from one end of the tongue part longitudinally across the body blank. This tongue part is bent from its blanking position, at right angles to the tearing strip, into the line or longitudinally of the tearing strip so that it then projects beyond the edge of the blank. After the can is formed, the 30 projecting tongue then extends in the conventional position beyond the seam.

To illustrate the invention there is disclosed in the drawing a container 11 (Fig. 1) having a bottom end 12 and a top end or cover 13 which are united with the body in the usual double 35 seam 14. A favorite type of tearing strip can at the present time embodies an inner collar which is shown in Figs. 1 and 2 and which is designated by the numeral 15. Such a collar may be located adjacent to and just beneath the cover 13 and may be united with the body wall in any suitable manner as by cooperating beads 16 formed in body and collar.

Such a collar backs up the tearing strip (indicated by the numeral 18) which preferably encircles the body and extends from one edge of a side seam 19 around the body wall and back to the other edge of the seam. It also provides for a seat for the cover when the latter is used as a reclosure for the can after opening and after the tearing strip has been removed.

A tearing strip tongue 21 is formed as an integral part of the body wall and projects beyond a lapped section 22 of the side seam 19. A lock seam section 23 is also formed in the side seam 55

19 and extends below the end of the lap section 22. Within the bottom double seam 14 the side seam has another lapped section 24.

Figs. 3, 4, and 5 illustrate a corner of the body blank which may be used to produce the container of Fig. 1. This blank wall (indicated by the numeral 25) is notched out at 26 adjacent an edge of the blank. A line of severance 27 is cut through the blank wall adjacent its edge, and 10 is preferably a composite line having a right angle long and short section as best illustrated in Fig. 3.

One end of the long section of the line terminates at 28 in a rounded part and the other end 15 joins the short section in a sharp corner. These line sections set off or form the tongue 21 which is in the plane of the blank wall 25 and which extends longitudinally along the edge of the blank and to one side of the edge notch 26. A 20 smaller notch 29 is made at the same time in the edge of and within the notch 26 and is located diagonally across from the rounded end 28 of the cut 27.

Parallel score lines 30 are cut in the blank 25 and extend substantially at right angles to the edge of the blank, one score line extending from the vertex of the notch 26, the other from a point adjacent the rounded cut 28. Supplemental or herringbone score lines 31 may also be 30 made in the tearing strip 18 these extending from the parallel score lines 30 in the usual manner.

After the blank has been scored the tongue 21 is first bent out of the plane of the blank and 35 into a position substantially at right angles to its former position (see Figs. 4 and 6). This places the tongue midway between the notches 26, 29 and a rounded loop part 35 is formed. This loop part 35 is then pressed down into a 40 close fitting folded section 36 (Figs. 5 and 7). This brings the tongue 21 substantially into the line of the tearing strip 18 where it extends beyond its end and beyond the edge of the blank.

The blank is then formed into a container in 45 the usual manner, at which time the edge of the blank adjacent the transverse line of cut 27 (indicated by the numeral 37) is formed into a hook part of the usual lock section 23 of the side seam 19. The remaining edge of the blank from which 50 the tongue was removed, this being between the section 37 and the tearing strip is lapped with the edge of the opposite side of the blank in the usual manner to produce the lap section 22 of the side seam.

55 An opening key 38 having a tongue engaging slot 39 may be conveniently secured as by a

spot weld 41 to the cover 13 and when it is to be used this key is lifted from the cover where it breaks off along a weakened notched part 42. When the tongue 21 is wound onto the key the notches 26, 29 assist in guiding the line of tear 5 into the scored lines 30 and the container is thus opened in the usual manner.

By constructing a tongue in this manner a great deal of material is saved in the blank which need only be large enough to form the desired 10 size of body, the lock seam section 23 determining the overall dimension of the blank. Since the tongue is extended beyond the edge of the body at the lap seam section 22, the tongue width comes out of a blank part about equal to that 15 forming the hook of the lock seam section 23 and consequently a much smaller blank produces the same size of can.

It is thought that the invention and many of its attendant advantages will be understood from 20 the foregoing description, and it will be apparent that various changes may be made in the form, construction and arrangement of the parts without departing from the spirit and scope of the invention or sacrificing all of its material 25 advantages, the form hereinbefore described being merely a preferred embodiment thereof.

I claim:

1. In a body blank for a tearing strip container, a tearing strip set off by score lines formed 30 in the body wall and adapted to be removed in opening the container, said tearing strip having a tongue formed as an integral part thereof extending at an angle to said tearing strip and disposed entirely within the marginal confines 35 of said blank, said tongue being adapted to be bent into line with said tearing strip and providing engaging means for an opening key.

2. A body blank for a tearing strip container 40 having a tearing strip set off by parallel score lines extending across the blank, a tongue constituting an integral part of the blank to provide a key engaging extension for one end of said tearing strip, said tongue extending at an angle to said tearing strip and defined by lines 45 of severance extending in and along the blank edge, whereby said tongue may be bent from its position in the plane of the blank into line with said tearing strip where it extends beyond the edge of the blank.

3. A tearing strip container constructed from a body blank as defined in claim 1.

4. A tearing strip container constructed of a body blank as defined in claim 2.

JOHN M. HOTHERSALL.
